CLAIM

The ornamental design for a vehicle seat, as shown and described.

DESCRIPTION

FIG. 1 is a rear perspective view of a vehicle seat showing our new design;

FIG. 2 is a frontal perspective view thereof;

FIG. 3 is a side elevational view of one side, the opposite side elevational view being a mirror image thereof; and,

FIG. 4 is a top plan view thereof.

The broken lines shown on the underside of the vehicle seat form no part of the claimed design.
